UNITED STATES PATENT OFFICE.

LEWIS HALLOCK NASH, OF SOUTH NORWALK, CONNECTICUT, ASSIGNOR TO
THE NATIONAL METER COMPANY, OF NEW YORK, N. Y.

FUEL-SUPPLY PUMP.

SPECIFICATION forming part of Letters Patent No. 674,385, dated May 21, 1901.

Application filed February 3, 1897. Serial No. 621,756. (No model.)

To all whom it may concern:

Be it known that I, LEWIS HALLOCK NASH, a citizen of the United States, and a resident of South Norwalk, in the county of Fairfield 5 and State of Connecticut, have invented certain new and useful Improvements in Fuel-Supply Pumps, of which the following is a specification.

My invention relates to gas or oil engines; 10 and it consists of an improved device for measuring and forcing the combustible liquid into the passage leading to the supply-port.

In the accompanying drawings I have shown 15 my invention applied in the form which is at present preferred by me; but it will be understood that various modifications and changes may be made therein without departing from the spirit of my invention and without exceeding the scope of the concluding claims.

In the accompanying drawings, Figure 1 is a vertical section through an oil-pump involving my invention, and Fig. 2 is a vertical section at right angles to the section of Fig. 1.

20 The following is a description of the structure illustrated in the drawings:

3 is an oil-supply pipe, and 4 is an overflow-pipe.

5 is a chamber or tank containing liquid 25 fuel—as, for example, gasolene.

6 is a submerged valveless cylindrical chamber open through passages 7' 7', Fig. 2, to the oil contained in the chamber 5.

7 is a duct, open to the air, through which 30 air enters to the inlet-port.

8 is a duct leading to the inlet-port.

The cylindrical chamber 6 is attached to a bearing 9 by means of webs 10 10. The bearing 9 is held in place by screws 11 11. By 40 removing these screws the bearing 9 and tube 6 can be removed from the casing.

12 is a plunger provided with a valveless longitudinal perforation 13, which plunger reciprocates in its bearings in the part 9 6.

45 The operation of the device is as follows: When the plunger is in the position shown in Fig. 2, liquid fuel enters the submerged chamber 6, through the passages 7' 7', by gravity. As the plunger 12 descends the oil 50 which is displaced from the submerged chamber 6 is forced through the perforation 13,

from which it escapes in the form of a jet and is carried by the current of air to the combustion-cylinder. It will be seen, assuming the plunger 12 to have a determined stroke, 55 that the same amount of oil will be forced out through the perforation 13 at each to-and-fro motion of the plunger. This is due in part to the fact that as the plunger is entering the submerged chamber it makes a sub- 60 stantially tight joint therewith and leaves no other escape for the oil contained therein than through the passage 13. It will also be evident that by increasing the throw of the plunger, so that it enters the chamber far- 65 ther, an increased amount of oil will be discharged from the pump at each to-and-fro motion thereof. Taking advantage of this fact I preferably control the throw of the plunger 13 by a governor device 15, which 70 may be of any suitable construction. By this contrivance I avoid in the supply-pump the use of auxiliary valves and positively control the amount of fuel supplied to the engine at each power stroke. 75

I have not illustrated nor described a gas or liquid-fuel engine in connection with this feeding device, as it may be applied to any suitable type of engine, either gas or liquid-fuel; but it will be understood that the duct 80 8 leads to the inlet port or ports of the power-cylinder, where the combined air and fuel are utilized to furnish the power for operating the same. It will be obvious that the passage 13, instead of being made in the plunger 85 itself, may be cut in the stationary walls of the submerged chamber.

What I claim is—

1. A feed-pump for oil-engines and the like, comprising a reciprocating plunger, a receiving-well and a cup submerged therein and adapted to snugly receive the plunger end, said parts being provided with an unobstructed discharge-duct freely connecting the interior of the cup with the engine. 90

2. A feed-pump for oil-engines and the like, comprising a plunger having a bore or duct therein extending inward from its end and having a side discharge-opening which has unobstructed communication with the oil-vaporizing chamber, a receiving-well and a cup submerged therein and adapted to snugly 100

receive said plunger, and means for reciprocating the plunger into and out of said cup.

3. A feed-pump for oil-engines and the like, consisting of a two-chambered casing, a plunger working through the wall or partition separating said chambers, and having a bore or duct extending from its end beyond said partition and opening freely into the other chamber, and a receiving-well having therein a cup or recess adapted to snugly receive the end of said plunger during a portion of its stroke.

4. A feed-pump for oil-engines and the like, comprising a two-chambered casing, one chamber acting as a receiving-well and the other as a discharge-chamber, means for supplying the receiving-well with oil, the partition between said chambers and the opposite wall of the discharging-chamber having seated openings in line, a member having a plunger-receiving bore adapted to be inserted within said casing-openings, the inner end of said bore forming a cup which is submerged in the oil-receiving well, and a plunger mounted within the bore in said member and having a duct extending from its end and provided with a side discharge-opening in its body.

5. A feed-pump for oil-engines and the like, comprising a reciprocating plunger, an oil-receiving well and a cup submerged in said well and adapted to snugly receive the plunger end, said plunger being provided with a discharge-duct connecting with the interior of the cup, combined with an automatically-variable plunger-reciprocating mechanism. 30

6. A feed-pump for oil-engines and the like, comprising a plunger having a bore or duct therein extending inward from its end and having a side discharge-opening, a receiving-well and a cup submerged therein and adapted to snugly receive said plunger, combined with an automatically-variable plunger-reciprocating mechanism. 35

7. In a pump the combination of a plunger having a freely-open discharge-duct communicating with the plunger end, a supply-well, a cup submerged in said well and adapted to snugly receive the end of the plunger, and means for reciprocating the plunger into and out of said cup. 40

LEWIS HALLOCK NASH.
